UNITED STATES PATENT OFFICE.

GEORGE ALBERT LYON, OF ALLENHURST, NEW JERSEY, ASSIGNOR, BY MESNE ASSIGNMENTS, TO AMERICAN CHAIN COMPANY, INC., A CORPORATION OF NEW YORK.

DUPLEX BUFFER CONSTRUCTION.

Application filed May 12, 1923, Serial No. 640,089. Renewed August 20, 1926.

This application is a partial continuation of my copending application, Serial No. 632,076, filed April 14, 1923, and contains subject matter taken therefrom.

This invention relates to automobile buffers or bumpers in which one or more of the adjustably connected buffer front elements may be advantageously formed of wide thin strip such as spring steel one and three-quarters to two and a half inches wide and one-quarter to three-eighths of an inch thick more or less, which may be recurved or otherwise formed as by being diagonally folded to form a transversely extending connector portion and several integrally connected transversely separated strip members which may be oppositely inclined adjacent the connector portion and extend in the same or opposite directions therefrom. Such a buffer element may be advantageously used at the lateral ends of the buffer adjacent the automobile wheels so that two transversely separated strips extend horizontally inward from this connector portion to form a double height or double strip buffer element which may extend inward to or past the center of the buffer, if desired, and be adjustably or otherwise joined in overlapping reenforcing position with similar horizontal strip members. Such a buffer front may be effectively mounted by one or more laterally extending rearwardly arranged supporting strips or members which may be integrally or rigidly connected to the front strips adjacent both ends of the buffer. For this purpose one or more of the vertically separated strip members may be bent backward so as to form, if desired, a laterally extending rear supporting or brace bar portion to be secured to the frame ends or other part of the automobile, said strip having, if desired, a forwardly extending end connector portion which may be clamped or secured to a front strip of the other element. In some cases also a unitary duplex element may be formed with folded or bent connector portions at both ends and, if desired, the vertically separated strips may both be bent rearward to form any desired type of supporting member such as a laterally extending brace bar portion to be connected to the automobile.

In the illustrative drawing showing in a somewhat diagrammatic way several embodiments of the invention

Figs. 1, 2 and 4 are front perspective views showing illustrative forms of buffers, and

Fig. 3 is a transverse section taken substantially along the line 3—3 of Fig. 2, showing the clamping device and cooperating connecting portions of the strips.

The buffer shown in Fig. 1 may comprise two buffer elements formed of relatively wide thin steel strip which may be hardened and tempered spring steel, if desired. Each element comprises a suitably folded or bent integral end connector portion such as 3, 10 which may, for instance, have the angular or diagonal folds 4, 6 so as to support in the desired vertically separated position the connected strip members 1 and 7, which may in this instance be forwardly arched, if desired, and have their strip ends 2, 8 on the other side of the buffer front so as to be clamped or connected to cooperating connecting portions 9, 11 of the other element 10. This connector portion may be similarly formed by suitable hot bending processes so as to form a strong and rigid connection for the vertically separated strips which may in this instance be bent rearward at 12, 20 so as to form the laterally extending portions 18, 19, which are adapted to be clamped or connected to the frame ends of an automobile by suitable integral or other brackets or connections. These rearwardly bent strips may have bent portions 14, 17 on the other side of the buffer connecting them to the strip ends 15, 16 which may form connecting portions arranged behind the front strips of the other element and adjustably or otherwise clamped or connected thereto as by the clamping devices 21. As is shown in Fig. 3, these clamping devices may comprise two vertically separated sockets or recesses to accommodate and more or less enclose the connecting portions or buffer strips. A heavy washer or retainer member 72 may be arranged behind the strips and clamped down upon them by the clamping bolt 73 and lock washer 74, so as to rigidly and securely hold all these parts in adjusted posi-

tion. In this way the buffer elements may be laterally adjusted throughout a range of several inches at least to accommodate different width automobiles or to have the ends 5 of the elements project further outward past the wheels, if desired.

The illustrative buffer shown in Fig. 2 may comprise two similar buffer elements formed of such steel strip and comprising 10 any suitable type of integral end connector portions. The connector portion 37 of the diagonally folded or bent type may thus connect the vertically separated strip members 35, 38 so that they are rigidly held at 15 the desired distance apart. The strip member 35 may extend across the buffer front in straight or forwardly arched position and have its connecting end 36 in cooperation with the front strip 47 of the other element 20 adjacent its connector portion. The other strip member 38 may be bent backward at 39 to form a rear supporting portion 40 that may extend laterally across the automobile front in the form of a brace 25 bar which may be clamped or secured to the frame ends or other parts of the vehicle. This strip may then be bent forward at 41 and be formed adjacent its end 43 with the connecting portion 42 adapted to be clamped 30 to the front strip 44 of the other element. This other similar element may have a connector portion 46 holding the vertically separated strip members 44, 47 in the desired 35 position. In this case 44 is the forwardly arched front strip having an end connecting portion 45, while the strip 47 is bent backward at 48 so as to form the supporting or 40 brace bar portion 49, and the forwardly bent portion 50 of this strip may have its connecting portion 51 adjacent the strip end 52 clamped to the other front strip 35 near the connector portion 37 thereof. This arrangement 45 makes it possible to form a single type of element for each size and weight of buffer and then these similar elements may be assembled in the reversed position illustrated in which they may be adjustably clamped by such clamping devices as are illustrated in Fig. 3.

50 Fig. 4 shows still another illustrative buffer in which a unitary duplex strip member is used in connection with one or more connected front strips or members of other type. This duplex member may comprise two integral end connector portions such as 65, rigidly supporting the adjacent strips 64, 66, in 55 vertically separated position. Each of these strips may be bent rearward at 63, 67 so as to form laterally extending supporting or 60 brace bar portions 62, 68 which may be vertically separated, if desired. The forwardly bent portions, 61, 69 of these strips connect with the front strips 60, 70 adjacent the other connector portion and of course these

strips may be welded or otherwise connected together at any desired part before or preferably after at least some of these bends or folds have been formed therein. Any desired type of front impact receiving member may be used with such an element and special stamped up or stiffened front plates or strips may be riveted or connected thereto, such as the forwardly arching front strips 54, 55 which may be welded, riveted or clamped to the front strips of the other element in any suitable way as by the bolts or rivets 56, 57, 58, and 59.

This invention has been described in connection with a number of embodiments, forms, proportions, sizes, parts, arrangements, materials, methods of construction, connection and use, to the details of which disclosure the invention is not of course to be limited, since what is claimed as new and what is desired to be secured by Letters Patent is set forth in the appended claims.

1. The automobile buffer comprising connected generally similar buffer elements formed of wide thin steel strip and each having an integral end connector portion at the lateral end of the element and angularly folded and formed to hold laterally projecting parts of the strip members in vertically separated position, one of said members extending partly across the buffer front and the other integral vertically separated member being bent to form a rearwardly extending supporting portion and having a connecting portion adapted to cooperate with the other element adjacent its connector portion.

2. The automobile buffer comprising connected buffer elements formed of wide thin steel strip and each having an integral end connector portion at the lateral end of the element and formed to hold laterally projecting parts of the strip members in vertically separated position, one of said members extending partly across the buffer front and the other integral vertically separated member being bent to form a rearwardly extending supporting portion and having a connecting portion adapted to cooperate with the other element.

3. The automobile buffer comprising connected generally similar buffer elements formed of wide thin steel strip and each having vertically separated horizontally extending strip members and an integral end connector portion at the lateral end of the element and adapted to project into protective position adjacent the automobile wheels, said strip members comprising two forwardly arched front strips extending across the central part of the buffer front and each having an end secured to a front strip of the other element adjacent its connector portion, said members comprising a pair of vertically sep-

arated rearwardly bent brace bar portions each having an end secured to a buffer front strip of the other element adjacent its connector portion.

4. The automobile buffer comprising connected generally similar buffer elements formed of wide thin steel strip and each having vertically separated strip members and an integral end connector portion at the lateral end of the element and adapted to project into protective position adjacent the automobile wheels, said strip members comprising two front strips extending across the central part of the buffer front and each having an end secured to a front of the other element, said members comprising a pair of rearwardly bent brace bar portions each having an end secured to a buffer front strip of the other element.

5. The automobile buffer comprising connected buffer elements formed of wide thin steel strip and each having vertically separated horizontally extending strip members and an integral end connector portion at the lateral end of the element, said strip members comprising a plurality of forwardly curved front strips extending across the central part of the buffer front and each having an end secured to a front strip of the other element adjacent its connector portion; said members comprising a plurality of rearwardly extending supporting portions each having an end secured to a buffer front strip of the other element.

6. The automobile buffer comprising connected buffer elements formed of wide thin steel strip and each having vertically separated strip members and an integral end connector portion, said strip members comprising a plurality of front strips extending across the central part of the buffer front and each having an end secured to the other element, said members comprising a plurality of rearwardly extending supporting portions each having an end secured to a buffer front strip.

7. The automobile buffer comprising connected buffer elements formed of wide thin steel strip and comprising a plurality of vertically separated strip members and an integral connector portion at the lateral end of the element to hold the adjacent strip members in vertically aligned position, said strip members comprising two front strips extending across the central part of the buffer front, said members comprising rearwardly extending supporting portions each secured to a buffer front strip of the other element.

8. The automobile buffer comprising connected buffer elements formed of wide thin steel strip and comprising a plurality of vertically separated strip members and an integral connector portion, said strip mem-

bers comprising front strips extending across the central part of the buffer front, each of said members comprising a rearwardly extending supporting portion secured to a buffer front strip of the other element.

9. The automobile buffer comprising connected buffer elements formed of wide thin steel strip and each having vertically separated strip members and an integral connector portion at the lateral end of the element to hold portions of said strip members in vertically aligned position, said strip members comprising front strips extending across the central part of the buffer front, said members comprising a pair of vertically separated rearwardly extending lateral supporting portions each secured to a buffer front strip of the other element.

10. The automobile buffer comprising connected buffer elements formed of wide thin steel strip and each having vertically separated strip members and an integral connector portion at the lateral end of the element, said strip members comprising front strips extending across the central part of the buffer front, said members comprising rearwardly extending lateral supporting portions each secured to a buffer front strip of the other element.

11. A horizontally resilient and vertically rigid automobile bumper comprising an impact receiving portion formed with duplex bars one above the other, and a portion to sustain said impact receiving portion, said sustaining portion being also formed with bars one above the other and connected together at their approximate ends in vertically rigid relation to each other.

12. A horizontally resilient and vertically rigid automobile bumper comprising an impact receiving portion formed with duplex bars openly spaced one above the other, and a portion to sustain said impact receiving portion, said sustaining portion being also formed with bars openly spaced one above the other, and connected together at their approximate ends in vertically rigid relation to each other.

13. A horizontally resilient and vertically rigid automobile bumper comprising an impact receiving portion formed with duplex bars openly spaced one above the other, and a portion to sustain said impact receiving portion, said sustaining portion being also formed with bars openly spaced one above the other and connected together at their approximate ends in vertically rigid relation to each other, said impact receiving portion being openly spaced from said sustaining portion its entire distance.

14. A horizontally resilient and vertically rigid automobile bumper comprising an impact receiving portion formed with duplex integral bars one above the other and ex-

tending approximately from end to end of the bumper.

15. A horizontally resilient and vertically rigid automobile bumper comprising an impact receiving portion formed with duplex integral bars one above the other and ex-

the bumper, and a portion to sustain said impact receiving portion, said sustaining portion being also formed with bars one ¹⁰ above the other and connected together at their approximate ends in vertically rigid relation to each other.
